DESIGN FOR AN OUTDOOR GRILL

Henry W. Lormor, Cleveland Heights, Ohio

Application June 19, 1944, Serial No. 114,091

Term of patent 7 years

(Cl. D81—10)

To all whom it may concern:

Be it known that I, Henry W. Lormor, a citizen of the United States residing at Cleveland Heights, in the county of Cuyahoga and State of Ohio, have invented a new, original, and ornamental Design for an Outdoor Grill, of which the following is a specification, reference being had to the accompanying drawing, forming a part thereof, in which

Fig. 1 is a perspective view of an outdoor grill embodying my new design; and

Fig. 2 is an end view thereof.

I claim:

The ornamental design for an outdoor grill, substantially as shown.

HENRY W. LORMOR.
